UNITED STATES PATENT OFFICE.

HIRAM B. NICKERSON, OF NEW BEDFORD, MASSACHUSETTS.

PIANO-FORTE STRAINING-PIN.

SPECIFICATION forming part of Letters Patent No. 441,438, dated November 25, 1890.

Application filed February 26, 1889. Serial No. 301,292. (No model.)

To all whom it may concern:

Be it known that I, HIRAM B. NICKERSON, a citizen of the United States, residing at New Bedford, in the county of Bristol and State of Massachusetts, have invented a new and useful Improvement in Piano-Fortes, of which the following is a specification.

My invention relates to the string-plate of a piano-forte and the device for giving the proper tension to the strings which are stretched thereon; and it consists in the peculiar construction of that part of the string-plate in which the devices for straining the strings are located, and in the peculiar construction of the straining devices, by means of which the strings are brought to the proper degree of tension, and also in the peculiar construction of the string-plate.

In the accompanying drawings, Figure 1 represents a view in perspective of a section of a string-plate of a piano-forte, showing my improved construction. Fig. 2 represents a plan view of a section of a device for preventing the string end of the straining devices from turning while tension is being given to the strings. Fig. 3 represents a view in cross-section of my improved straining device and the straining-abutment in which it is located. Fig. 4 represents a view of my improved straining device as it appears when removed from the straining-abutment and showing the manner of attaching the string to the same. Figs. 5, 6, 7, and 8 are views of a different construction of the string end of my improved straining device. Fig. 9 is a view in vertical cross-section of my improved string-plate, showing the strings passing through the plate.

In Fig. 1, *a* represents a section of the string-plate of a piano-forte, the upper portion *b* of which is deflected to the rear, and then brought forward to practically form the arc of a circle, as *l*, whose center is the bridge *t*. *f* represents the strings of the piano-forte. *e* represents a block, preferably of metal, having apertures *g*, provided with grooves *h*, which loosely enclose the string ends of the straining devices. The strings of the piano are attached to the ends of the straining devices by passing the end through the perforation *j* and then coiling it about itself, as at *s* in Figs. 3, 4, and 5. The wire which projects beyond the circumference of the straining device fits in the

groove *h*, and thus the device is prevented from turning when tension is being given to the string.

In Fig. 3, *m* is a rod having head *o*, chisel-point *p*, and laterally-perforated at *j*. *n* is a tube having exteriorly-squared top *r* and interior shoulder *w*, and screw-threaded on the outside to correspond with screw-thread in the straining-abutment *l*. The rod *m* is inserted in the tube *n* and the string *f* attached, as shown in Fig. 4, and the tube *n* is then screwed into the straining-abutment *l* from the under side, and then by a key or wrench is revolved to the left until the string has the proper tension.

In Figs. 5, 6, 7, and 8 is illustrated a different construction of the string end of the straining device. Fig. 5 shows the string attached to the end of the straining device in the proper manner, while Figs. 6 and 7 show the manner in which the grooves in which the loop of the string lies are cut, while Fig. 8 shows the direction and depth of the grooves on the end of the bar. The groove *i* is cut diagonally across the end of the bar and of such a depth that the pull of the string when it is attached, as in Fig. 5, will be from the center. The groove *k* is cut parallel with the length of the rod and directly in line with the perforation *j*, as is fully shown in Fig. 7.

In Fig. 9 the top of the string-plate is deflected to the front and then carried to the rear to form the arc of a circle whose center is the apertures *q*, through which the strings *f* pass to the front of the plate and over the bridge *t*.

What I claim, and desire to secure by Letters Patent, is—

1. In a piano-forte, the combination of a string-plate having its top deflected to the rear and then brought forward in the arc of a circle whose center is practically the bridge, and having located in said arc straining devices consisting of a round rod screw-threaded in a portion of its length and a nut to fit said screw-thread and provided with a transverse hole for the attachment of the string, so that when the string is attached its thickness will lie outside of the circumference of said rod, with a bar of metal or other suitable material adapted to lie against the deflected portion of the string-plate and apertured to loosely

inclose the lower ends of said straining devices, said apertures provided with grooves in their sides adapted to receive that part of the loop of the string which projects beyond the circumference of said straining - rod, whereby the said rod is prevented from turning while tension is given to the string, all as shown and described.

2. In a piano-forte, a straining device consisting of a rod provided with a chisel-point

p, lateral aperture *j*, and head *o*, and the tube *n*, exteriorly screw-threaded and provided with squared top *r* and having interior shoulder *w*, on which the head of the rod *m* rests, all as shown and described.

HIRAM B. NICKERSON.
